Primary Examiner — R. Johnson(74) Attorney, Agent, or Firm — Neal, Gerber & Eisenberg LLP(57) CLAIM

The ornamental design for a shoulder rest for a violin or viola as shown and described.

DESCRIPTION

FIG. 1 is an upper perspective view of a shoulder rest for a violin or viola in accordance with our design.

FIG. 2 is a first side view thereof.

FIG. 3 is a lower perspective view thereof.

FIG. 4 is a top view thereof.

FIG. 5 is a front view thereof.

FIG. 6 is a bottom view thereof.

FIG. 7 is another upper perspective view thereof.

FIG. 8 is a second side view thereof; and,

FIG. 9 is another lower perspective view thereof.

The broken lines represent portions of the shoulder rest for a violin or viola that form no part of the claimed design.

1 Claim, 9 Drawing Sheets(56)
